UNITED STATES PATENT OFFICE

KENNETH J. HINES, OF FALLS CHURCH, VIRGINIA

DESIGN FOR A LUNCH STAND

Application filed March 23, 1933. Serial No. 47,549. Term of patent 3½ years.

To all whom it may concern:

Be it known that I, KENNETH J. HINES, a citizen of the United States, residing at Falls Church, in the county of Arlington and State of Virginia, have invented a new, original, and ornamental Design for a Lunch Stand, of which the following is a specification, reference being had to the accompanying drawing, forming part thereof.

The rear of the lunch stand has two windows therein of the type shown in Figure

1 and the side of the lunch stand not shown in the drawing has an entrance door therein.

I claim:

The ornamental design for a lunch stand as shown and described.

KENNETH J. HINES.
